Primary Examiner — Cynthia Underwood*(74) Attorney, Agent, or Firm* — Morrison & Foerster LLP(57) **CLAIM**

We claim the ornamental design for a fan, as shown and described.

DESCRIPTION

FIG. 1 is a perspective view of a fan showing our new design;

FIG. 2 is a front view thereof;

FIG. 3 is a back view thereof;

FIG. 4 is a side view thereof;

FIG. 5 is a side view of the opposite side of FIG. 4;

FIG. 6 is a top view thereof; and,

FIG. 7 is a bottom view thereof.

The broken lines represent environment and the boundary lines represent the bounds of the claim and form no part of the claim.

1 Claim, 6 Drawing Sheets---
